UNITED STATES PATENT OFFICE.

JOSEPH R. JACKSON, JR., OF BOSTON, MASSACHUSETTS, ASSIGNOR TO ALONZO B. SEE,
OF BROOKLYN, NEW YORK.

ELEVATOR.

1,291,530.

Specification of Letters Patent. Patented Jan. 14, 1919.

Application filed November 6, 1915. Serial No. 59,976.

To all whom it may concern:

Be it known that I, JOSEPH R. JACKSON, Jr., a citizen of the United States, and a resident of Boston, in the county of Suffolk and 5 Commonwealth of Massachusetts, have invented an Improvement in Elevators of which the following description, in connection with the accompanying drawings, is a specification, like characters on the drawings 10 representing like parts.

This invention relates to elevators and more particularly to electrically operated elevators, and among other objects provides devices for facilitating the control thereof 15 and contributing to the safety and comfort of the passengers.

The character of the invention may be best understood by reference to the following description of an illustrative embodiment 20 thereof shown in the accompanying drawings, wherein,—

Figures 1, 2 and 3 collectively show diagrammatically an elevator car, operating and controlling instrumentalities and electrical 25 circuits and connections therefor;

Fig. 4 is a view showing a side elevation of an elevator car in an elevator well extending through several floors of a building, a motor, brake and other devices for controlling the 30 car;

Fig. 5 on an enlarged scale is a front elevation of the elevator car in a section of its well and controlling instrumentalities associated therewith;

Fig. 5^a is a detail of a device shown in Fig. 5;

Fig. 6 is an end elevation of the car shown in Fig. 5 and a vertical section through a portion of the wall of the well showing a 40 floor door and means for interlocking said door with the car door;

Fig. 7 on an enlarged scale is a horizontal section taken on line 7—7 of Fig. 6;

Fig. 8 on an enlarged scale is a view partly 45 in side elevation and partly in vertical section of a combined electro-magnetic opening device and check for the car door; and

Fig. 9 is a view partly in side elevation and partly in vertical section of a timing device for controlling the switch for breaking the circuit to the door opening device.

Referring to the drawings, the illustrative

apparatus shown therein as embodying the invention comprises an elevator car 5 (Fig. 4) carried by a sling 6 and adapted to travel 55 in a well 7 extending through several floors of a building, four floor levels being shown herein for the purpose of illustration. The car is carried by a cable 8 passing about suitable guide pulleys and connected to a winding drum 9 shown herein located at the lowest floor level. This drum has a worm wheel 11 fast thereon meshing with a worm 13 on a shaft 15 of an electric motor 17. The motor shaft is provided with the usual electro-magnetically operated brake 19.

The drum shaft has a sprocket wheel 21 thereon connected by a sprocket chain 23 with a sprocket wheel 25 which rotates a floor selector wheel 27 to be described.

Panels 29 and 31 are located adjacent the 70 motor and carry electrical instrumentalities to be described.

Referring now to Fig. 5, the elevator car is provided with a door or gate 33 connected 75 by hangers 35 with rollers 37 adapted to travel on a track 39 mounted on the body of the car.

An important feature of the invention relates to means for automatically opening the 80 car door on its arrival at a floor level. To accomplish this an electro-magnetic device is provided typified herein in the form of a solenoid 41 mounted on a bracket 43 carried by the top beam of the usual sling carrying 85 the car. This solenoid is provided with a core, or plunger 45 projecting through and beneath the coil of the solenoid and having an end pivotally connected to a short arm of a bell crank 47 fulcrumed on a pin on a 90 bracket 49 mounted on the body of the car and having its long arm connected by a link 51 with the car door 33.

When the solenoid is energized as more fully hereinafter described, its plunger is 95 drawn upward, thereby rocking the bell crank 47 in a clockwise direction and sliding the door along its track to the left of Fig. 5 to open the same.

Another important feature of the invention relates to means for cushioning the opening movement of the door and automatically closing the door. To accomplish this a cylinder 53 (Figs. 5 and 8) is mounted on the

top of the solenoid coil and contains a piston 55 fast on the upper end of the solenoid plunger 45 referred to. A helical spring 57 is confined between the upper face of said 5 piston and the head 59 of said cylinder. This spring will serve to cushion the opening movement of the door and the energy developed by thus compressing the spring will be available for subsequently automatically 10 closing the door on the deenergization of the solenoid coil as more fully hereinafter described.

To prevent the slamming of the door, means is provided for checking its closing 15 movement. To this end a valve is provided for the cylinder 53 communicating with the space between the piston and the lower end of the cylinder, said valve being shown herein in the form of a screw 61 tapped into said 20 cylinder adjacent the lower end thereof and having a seepage port 63 therein. A washer 65 of leather or other suitable material is interposed between the head of the screw and the cylinder. The screw will permit air to 25 seep slowly through its port 63 and escape between the head of the screw and said washer with greater or less freedom depending on the tightness with which the screw is adjusted to said washer and thus the closing 30 of the door may be gradually checked as required. To limit the checking effect of said valve, to the final closing movement of the door, the cylinder may have a port 64 intermediate the ends thereof which will permit 35 the air beneath the piston to escape freely until the piston reaches said port in its downward movement. Then the valve screw 61 will serve to check the further movement of said piston.

40 To permit the automatic, simultaneous opening of the car door 33 and the door at the floor level opposite thereto, suitable means may be provided for interlocking the doors on the arrival of the car at said level.

45 To accomplish this a latch 67 (Figs. 5, 6 and 7) is pivoted on a lug 69 projecting from the car door and is adapted to be rocked into a vertical channel 71 on the floor door. To hold this latch out of range 50 with said channel excepting when the car is at a floor lever, there may be provided a rod 73 having its lower end connected to an elongated eye in said latch and its upper end connected to the core 75 of a solenoid 77 mounted on the car body. This solenoid is energized by the completion of a circuit, to be described, so long as the car is traveling between floors, but on the arrival of the car at a floor this solenoid is de- 55 energized and its core is permitted to drop and permit the latch 67 to rock into the channel 71 as shown in dotted lines in Fig. 7. To render the downward movement of the rod 73 more positive, a helical spring 79 60 encircling the same is mounted on the rod

and confined between a fixed guide 81 on the car door and a plunger 83 on the rod.

To lock the car door in closed position excepting when it is at a floor level and the solenoid 77 is deenergized, the bracket carrying the solenoid may be provided with a stop 85 (Figs. 1 and 5^a) adapted to be engaged by a heel 87 on the upper end of the latch rod 73. This heel will be in line with the stop 85 when the solenoid is energized 75 and thereby will prevent the opening of the door, but on the deenergization of the solenoid said heel will drop down out of line with said stop and will no longer prevent the opening of the door. The upper end of 80 the latch rod is also provided with a forked toe 89 adapted to receive the solenoid plunger 75 and engage the head 75^a of said plunger when the door is in its closed position. When the plunger drops and the heel 87 is 85 out of range with the stop, this forked toe may slide away and separate from said plunger on the opening of the door and on the closing of the door it will automatically re-engage said plunger.

To yieldingly limit the downward rocking movement of the latch 67, a spring finger 91 (Fig. 6) may be mounted on the door beneath the latch. This will serve to appropriately limit the downward rocking of 95 the latch and hold the same in horizontal position to connect the car and floor doors, but will yield and permit the latch to rock down beyond its horizontal position in the course of the upward travel of the car in 10 case the latch strikes any obstacle on the wall of the well.

The doors in the wall of the well at the different floor levels should be locked in closed position excepting when the car is 10 opposite a floor level. To accomplish this each floor door is provided with a latch bar 93 (Fig. 1) adapted to interlock with a dog lever 95 pivoted on the well wall adjacent the door and having a roller 96 adapted to 11 be engaged by a long vertical lever 97 having its lower end pivoted on a bracket 99 at the lower end of the car and its upper end pivotally connected to toggle links 101, the meeting ends of which are pivotally connected by a link 102 to a plunger 103 of a solenoid coil 105.

This solenoid is energized while the car is running by a circuit to be described, and thereby draws its plunger upward buckling 12 the toggle links as shown in Fig. 1 and holding the lever 97 out of range with the roller of the dog lever 95. When, however, the car is arrested at a floor level, the solenoid coil 105 is automatically deenergized, thereby permitting its plunger 103 to gravitate downward and straighten the toggle links 101 and rock the lever 97 in a clockwise direction (Fig. 1). In the course of this movement it engages the roller of the dog 13

lever and rocks the latter in a contra-clockwise direction, disengaging the same from the floor door latch 93. The door is now free to be opened with the car door.

5 An important feature of the invention relates to means for holding the doors open for a predetermined length of time to allow a passenger to enter the car without interference or hindrance by the closing of the door. As stated the doors are automatically opened by the energization of the solenoid 41. Obviously, the door cannot close until the circuit to the solenoid is broken. To accomplish this there may be provided a timing device typified herein in the form of a solenoid 107 (Fig. 2) provided with a plunger 109 having a lug 111 thereon adapted to open a switch 113 in the circuit to the door opening solenoid, thereby deenergizing the latter and permitting its spring 57 to become effective to rock the bell crank 47 in a contra-clockwise direction and close the doors. The timer solenoid is energized simultaneously with the door opening solenoid, but the plunger of the former is restrained and moves slowly upward from its position shown in Fig. 2, so that a substantial interval of time elapses before its lug moves up into engagement with the 30 switch 113. To check the upward movement of the plunger, a suitable retarding device may be provided typified herein in the form of a cylinder 115 (Fig. 9) mounted on said solenoid and containing a piston 117 fast on the upper end of the solenoid plunger 109. The cylinder has a head 119 provided with a valve 121 similar to the valve described for the door check cylinder 53 whereby the air is permitted to seep gradually from the space in the cylinder above the piston and thereby check the upward movement of said piston. By adjusting the escape valve the air may be permitted to escape more or less freely as desired and the 40 upward movement of the piston may be varied so that any interval of time desired may elapse before the plunger lug 111 will be effective to shift the switch 113 and deenergize the door opening magnet and permit the doors to close.

The timer solenoid plunger should drop quickly on the deenergization of the solenoid to allow the switch 113 to close promptly thereafter. To permit this the cylinder has 55 a port 122 adjacent the lower end thereof which will permit the air to escape freely from the cylinder on the downward movement of the plunger.

The elevator car may be provided with a 60 dome light 123 (Fig. 1) which will be automatically lighted when a push button at a floor is pressed to summon the car and will remain lighted while the car is in use. The car may also be provided with a light 125 adjacent the threshold of the car door to

enable the passenger to see clearly the thresholds of the car and floor doors and thereby assist him in avoiding making any misstep in the event that the thresholds should not be in registration. Means is 70 provided for automatically lighting the threshold light while the doors are open.

The car is provided with a panel conveniently mounted at the side thereof carrying push buttons 127 corresponding to 75 the number of the floors of the building. For purposes of illustration four such push buttons are shown within the car numbered,—1, 2, 3 and 4. When any one of these buttons is pressed, it will despatch the car to the floor corresponding thereto. The panel is also provided with a stop button 129 adapted to be pressed to arrest the car while traveling between floors, but without 80 opening the car door.

The floors are provided with push buttons 131 (Figs. 1 and 4) located adjacent the floor doors and numbered in Fig. 1 of the diagram,—1, 2, 3 and 4 to correspond with the floor levels. If it is desired to summon 90 the car from one floor to another, the push button at the floor of the operator is pressed, thereby despatching the car to said floor.

Having described various instrumentalities of the apparatus next will be described 95 circuits and electrical connections therefor.

The circuit for the electric motor 17 comprises a main positive conductor P (Fig. 3) connected by a conductor α with a contact segment 133, the latter being connected by a conductor α' with the series field 17^c of said motor, said field being connected in turn by a conductor α'' with a contact segment 135 adjacent the contact segment 133, said segment 135 being one of a series of similar segments connected with resistances 137. A contact 139 carried by an arm 141 is adapted to slide over said resistance contacts and cut out resistances to increase the speed of the motor. This is accomplished automatically by a holding magnet 143 containing a plunger 145 connected by a link 147 with the arm 141. When this magnet is energized as more fully hereinafter described, it will cause the arm 141 to swing upward and progressively cut out the resistances and increase the speed of the motor. Too rapid movement of the arm is prevented by a dash pot 149.

The arm 141 is connected by a wire α^2 120 with a fixed contact 151 adapted to be connected by a bridge contact 153 with a fixed contact 155. This bridge contact is carried by a lever 157 fulcrumed intermediate its ends and adapted to be rocked to cause said 125 bridge contact to connect with said fixed contacts by a magnet 159 adapted to be energized by a circuit to be described to cause the car to travel upward.

The fixed contact 155 is connected by a con- 130

ductor a^4 with the motor armature 17^a connected in turn by a conductor a^5 with a fixed contact 161 adapted to be connected by a bridge contact 163 with a fixed contact 165, said bridge contact being carried by the magnet operated lever 157 referred to. The fixed contact 165 is connected by a conductor a^6 with a conductor a^7 leading to the main negative line N.

10. To supply current to the shunt field 17^b of the motor, a conductor a^8 is tapped from the conductor a^7 referred to and is connected by a conductor a^9 with a fixed contact 167 adapted to be connected by bridge contact 169 with a fixed contact 171, said bridge contact being carried by the magnet operated lever 157. The fixed contact 171 is connected by a conductor a^{10} with the shunt field 17^b of the motor, the latter being connected by a conductor a^{11} with the conductor a^{12} connected to a fixed contact 173 adapted to be connected by the bridge contact 163 referred to on the lever 157 with the fixed contact 165 connected by the conductors a^6 and a^7 with the main negative line.

Thus when the lever 157 is rocked by its magnet in a clockwise direction (Fig. 3), it will bridge the fixed contacts described and complete the circuit for rotating the motor in a direction for causing the elevator car to travel upward in its well.

When the circuit is thus completed to the motor, a circuit is also completed to the magnet 19 for releasing the brake. To accomplish this a conductor b is tapped from the conductor a^{10} and is connected to the brake magnet 19, said magnet being connected by a conductor b' with the conductor a^{12} connected by the fixed contact 173, bridge contact 163, and fixed contact 165 with the conductors a^6 and a^7 leading to the main negative line.

When the lever 157 is rocked to cause its bridge contact 169 to connect the fixed contacts 167 and 171, it also completes the circuit to the magnet 143 for pulling up the arm 141 and cutting out resistances in the series field. This circuit comprises a conductor m connecting the fixed contact 171 with the fixed contact 174 adapted to be connected by a swinging arm 174^a with a conductor m' connected to the magnet 143. This magnet is connected by a conductor m^2 with the conductor u^2 referred to, leading to the conductor a^6 and the main negative line N. On the energization of this magnet its plunger 147 will be pulled slowly upward as checked by the dash pot 149 and thereby progressively cut out resistances in the series field to increase the speed of the motor and eventually completely cut out the series field when the arm contact 139 reaches the contact segment 133 referred to.

When the motor is to be rotated in a direction for causing the elevator to travel

downward in its well, a lever 175 is rocked in a contra-clockwise direction (Fig. 3) by the energization of a magnet 177, thereby completing the circuit to the motor for reversing the same and also completing the circuit to the brake magnet for releasing the same.

Since the bridge contact carrying levers and their circuits for controlling the direction of the motor and the releasing of the brake are of usual construction, further description thereof is unnecessary herein.

The levers 157 and 175, their controlling magnets and the contacts co-operating with said levers may all be mounted on the panel 29 (Fig. 5) referred to adjacent the motor.

Next will be described devices and electrical connections therefor for energizing the magnet 159 for rocking the switch lever 157 in a clockwise direction to cause the car to travel upward to a selected floor.

This is accomplished by pressing either a button in the car or a floor button corresponding to the floor to which it is desired to send the car. Since the circuits and devices completed by pressing the buttons to send the cars to the various floors are similar, a description of the circuit and devices co-operating therewith for one will suffice for all.

For purposes of illustration it may be supposed that the car is at the first floor and it is desired to summon the same to the second floor. To accomplish this the push button 131 at the second floor is pressed. The circuit completed by the pressing of this button comprises a conductor c (Fig. 3) tapped from the conductor a leading from the main positive line P, said conductor c being connected by a conductor c^1 with a hand switch 179. This switch is connected by a conductor c^2 (Figs. 1, 2 and 3) with a fixed contact 181 mounted on the body of the car and adapted to be connected by a switch 183 with a fixed contact 185. This switch is urged away from said fixed contacts to open the circuit by a spring 187. To close the switch it is provided with a stem 189 adapted to be engaged by a cam finger 191 mounted on the car door and so arranged that it will hold the switch closed when the door is shut but will permit the switch to open when the door is opened. The fixed contact 185 is connected by a conductor c^3 with a fixed contact 193 mounted on the well wall adjacent a floor door. This fixed contact is adapted to be connected by a switch 195 with a fixed contact 197. The switch has a stem 199 adapted to be pressed downward to connect the fixed contacts by the cam finger 93 referred to mounted on the floor door. When the floor door is opened a spring 201 pushes the switch 195 upward and disconnects the same from said fixed contacts. The floor door operated switch 195 just described

is located adjacent the fourth floor. The fixed contact 197 is connected by a conductor c^4 with a fixed contact 203 adjacent the third floor door adapted to be connected by a switch 205 with a fixed contact 207, the latter being connected by a conductor c^5 with a fixed contact 209 adjacent the second floor door and adapted to be connected by a switch 211 with a fixed contact 213. 10 This fixed contact is connected by a conductor c^6 with a fixed contact 215 adjacent the first floor door adapted to be connected by a switch 217 with a fixed contact 219.

The switches 205, 211 and 217 for the 15 third, second and first floors are controlled by the doors at their floors by cam fingers similar to that described for the fourth floor.

A fixed contact 219 is connected by a conductor r with a fixed contact 220, connected in turn by a switch 220^b to be referred to, with a fixed contact 220^c. The latter is connected by a conductor r' (Figs. 2 and 3) with a fixed contact 221 adapted to be connected by a switch 223 on the motor speed regulator arm 141 referred to with a fixed contact 225. The switch 223 will be hereinafter referred to as the non-interference switch because after either a car or a floor 30 button is pressed to despatch the elevator it prevents interference with the control of the elevator by any of the other push buttons in the car or at the floors for despatching the car to different floors.

35 The fixed contact 225 is connected by a conductor f (Figs. 1, 2 and 3) with branch conductors one of which f' leads to the car push buttons 127 and the other branch f'' leads to the floor push buttons 131.

40 It will be recalled in the example selected it is assumed it is desired to call the car from the first floor to the second floor. A branch conductor f'' leads from the conductor f'' to a fixed contact 227 adapted to be connected by a switch controlled by the second floor push button 131 with a fixed contact 231. This fixed contact is connected by a conductor 2 (Figs. 1, 2 and 3) with the coil of a floor magnet 233 (Fig. 3) for the second floor. This magnet is connected by a conductor 2' with a branch conductor 2² leading to a fixed contact 235, and with a branch conductor 2³ leading to a fixed contact 237. 45 The fixed contact 235 is adapted to be connected by a switch 239, to be described, with a fixed contact 241, the latter being connected by a conductor 2⁴ with a conductor u leading to the magnet 159 for rocking the lever 157 to cause the motor to rotate in a direction to cause the elevator car to travel upward. The magnet 159 is connected by a conductor u' with a conductor u^2 connected to the conductor o^6 referred to leading to the main negative line N.

50 The fixed contact 237 referred to is adapt-

ed to be connected by the switch 239 with a fixed contact 243 connected by a conductor 2⁵ with a conductor d leading to the magnet 177 for operating the lever for completing the circuit for causing the motor to rotate in a direction to lower the elevator. 70

When the elevator is beneath the second floor, the switch 239 will bridge the contacts 235 and 241 in readiness to complete the circuit to the up-magnet 159 on the pressing of a car or a floor button, and when the car is above the second floor the switch 239 will bridge the contacts 237 and 243 in readiness to complete the circuit to the down-magnet on the pressing of a car or a floor button. 80 When the switch 239 is in mid position the car is at the second floor and the switch will interrupt the circuits to both the up and down magnets and then the pressing of a car or floor button on the second floor would not cause the car to leave the second floor level. 85

To cause the switch 239 to shift automatically in accordance with the travel of the elevator it is made in the form of a bell crank having a short arm 245 provided with a follower pin 247 projecting into a cam slot 249 on the selector wheel referred to. This wheel as stated is rotated by the winding drum for causing the car to travel up and down. The contour of the cam slot is such that in the course of the rotation of the selector wheel the switch 239 will be brought automatically to its mid position when the car is at the second floor; to its position in readiness to complete the circuit to the up-magnet when the car is beneath the second floor; and in its position in readiness to complete the circuit to the down-magnet when the car is above the second floor. 100 105

A switch such as described is provided on the selector for each of the other floors and since the principle of operation is the same for all and the selector is of usual construction, further description thereof is unnecessary. 110

When the push button 131 at the second floor is pressed it will complete the circuit as described to the up-magnet 159. This will rotate the lever 157 in a clockwise direction and complete the circuits described to the motor and rotate the same in a direction to cause the car to travel upward. It will also energize the brake magnet and release the brake. 115 120

It will be recalled this circuit passes through the car door controlled switch and the floor door controlled switches. These switches are closed only when their doors are closed and therefore they prevent the starting of the car until after all of said doors are closed. 125

It will be recalled the circuit to the up-magnet passes through the non-interference switch 223. The arm 141 carrying this 130

- switch as stated is moved upward on the energization of the magnet 143 in starting the motor. This automatically opens the non-interference switch 223 and renders all of 5 the other car despatching buttons ineffective. In order that the circuit to the up-magnet 159 may be complete after the breaking of the circuit by the non-interference switch, a conductor r^3 (Fig. 3) is tapped from the 10 conductor r^2 and is connected to a fixed contact 251 (Fig. 3) directly above the fixed contact 174 referred to. The arm 141 carrying the non-interference switch, in the course of its upward movement, shifts the arm 174^a 15 upward, thereby disconnecting the same from the contact 174 and connecting the same with the contact 251. The second floor magnet 233 referred to is provided with an armature 233^a adapted to connect a 20 fixed contact 253, connected to the conductor 2, with a fixed contact 255, connected in turn by a conductor 2^6 with the conductor r referred to. When the push button 231 for the second floor is pressed to energize the 25 magnet 233, it will attract its armature 233^a and connect the contacts 253 and 255. The closing of the circuit at this point and the shifting of the switch arm 174^a up into engagement with the fixed contact 251 will now 30 continue the completion of the circuit to the up-magnet and continue the completion of the circuit to the hold-up magnet 143 independently of and free from control by all of the car despatching push buttons. 35 The motor will continue to rotate to elevate the car until the car arrives at the second floor, then the selector switch 239, following the travel of the car, will move to its mid position and break the circuit to the 40 motor and to the brake, thereby automatically arresting the former and applying the latter. The hold-up magnet 143, however, will continue to be energized and hold open the non-interference switch and prevent the 45 starting of the car by the despatch buttons until after the car door has been opened and closed as more fully hereinafter described. On the arrival of the car at the floor level, as stated the floor door magnet 105 is deenergized and permits its plunger to drop and straighten the toggle links, thereby rocking the long lever 97 (Fig. 1) in a clockwise direction and releasing the floor door locking dog 95. 50 Next will be described the circuit for energizing the floor door unlocking magnet 105. This circuit comprises a conductor o (Figs. 1, 2 and 3) tapped from the conductor b leading to the brake magnet 19 referred to and leading to the door unlocking magnet 105 (Fig. 1). This magnet is connected by a conductor o' with the conductor b' referred to, leading from the brake magnet to the main negative line N. 55 Thus on the deenergization of the brake

magnet to apply the brake the door unlocking magnet 105 is deenergized, thereby unlocking the floor door.

Also simultaneously with the deenergization of the brake magnet, the magnet 77 referred to, is deenergized for unlocking the car door and interlocking the car door with the floor door. The circuit for the magnet 77 comprises a conductor o^2 tapped from the conductor o leading to the floor door unlocking magnet and connected to said car door unlocking magnet 77. The latter is connected by a conductor o^3 with the conductor o' leading from the floor door unlocking magnet to the brake magnet. 75 80

On the deenergization of the magnet 77 its plunger will drop and with it the latch rod 73 (Fig. 5), thereby causing the heel at the upper end of said rod to move down out of line with the door locking stop and permit the door to slide open. In the course of this opening movement the forked toe of said rod disengages the plunger of the magnet 77. 85

The car is now at a floor level and the car door and the floor level door opposite thereto are unlocked and interlocked in readiness to be opened. To accomplish this, the door opening solenoid 41 referred to is energized. The circuit for this solenoid comprises a conductor x (Fig. 2) which may be tapped from the main positive line and be connected by a conductor x' with the coil of said door opening solenoid (Fig. 1). This coil is connected by a conductor x^2 90 with a fixed contact 257 (Fig. 1) adapted to be connected by a switch 258 with a fixed contact 257^a connected in turn by a conductor x^3 with a fixed contact 259 (Fig. 2) at the timer solenoid for controlling the 95 length of time the doors are held open. This fixed contact 259 is normally connected by the timer switch 113 referred to, with a fixed contact 261, said switch being urged in its position shown by a spring 263. The 100 fixed contact 261 is connected by a conductor x^4 with a fixed contact 265 adapted to be connected by a switch 267 with a fixed contact 269. The switch 267 is mounted on an armature of what may be termed the 105 pilot magnet 271 adapted to be energized as more fully hereinafter described. The fixed contact 269 is connected by a conductor z with a fixed contact 273 on the push button panel in the car (Fig. 1), said fixed 110 contact being adapted to be connected by a switch 275 with a fixed contact 277. The switch 275 is normally maintained in the position shown to connect the fixed contacts 273 and 277 by the spring 279. The switch 115 is adapted to be shifted to break said connection by the pressing of the push button to start the car. The fixed contact 277 is connected by conductor z' , z^2 and z^3 in series 120 with fixed contacts controlled by the push 125 button 278. The switch 275 is normally maintained in the position shown to connect the fixed contacts 273 and 277 by the spring 279. The switch 275 is adapted to be shifted to break said connection by the pressing of the push button to start the car. The fixed contact 277 is connected by conductor z' , z^2 and z^3 in series 130 with fixed contacts controlled by the push button 278. 135

buttons for the other floors. The fixed contact 281 at the push button for sending the car to the fourth floor is connected by a conductor z^4 with a coil for the pilot magnet 271 referred to, said coil being connected by a conductor z^5 with the main negative line N. The circuit described for energizing the door opening solenoid 41 is normally closed excepting where interrupted by the switch 267 at the pilot magnet 271.

Next will be described a circuit for energizing the pilot magnet on the arrival of a car at a floor level. This circuit comprises a conductor z^6 (Fig. 2) tapped from the positive line x referred to and leading to a fixed contact 283 adapted to be connected by a normally closed switch 285 with a fixed contact 287. The switch 285 is mounted on an armature 289 coöperating with a magnet 291 adapted to be energized by the pressing of the car stop button 129 referred to. The fixed contact 287 is connected by a conductor z^7 with a fixed contact 293. This contact is adapted to be connected by a normally open switch 295 with a fixed contact 297. The latter is connected by a conductor z^8 with the conductor z^4 leading to the negative line through the pilot magnet 271 as described.

30 The switch 295 is mounted on a lever 299 having an arm 301 connected to the lever 299 in the manner of a knife blade so that when the arm 301 is rocked downward it will be effective to rock the lever 299 upward to close the switch 295, but said arm 301 will be free to rock upward without affecting the position of the lever 299.

The switch 295 is controlled by a master magnet 303 in the form of a solenoid containing a plunger 305 having a nub 307 thereon. When the magnet is energized the plunger will be drawn upward with its nub above the lever arm 301, but when the magnet is deenergized the plunger will drop and cause its nub to engage said arm and close the switch 295. As the nub moves downward it will escape past the switch and the latter will be opened by its spring 309. To check the fall of the plunger when its magnet is deenergized, the upper end of said plunger may be connected to a piston 311 in a cylinder 313 provided with a valve 315 permitting the gradual escape of the air therefrom and the gradual drop of the plunger.

55 The master magnet 303 is energized at the same time the brake magnet is energized to release the brake. The circuit for the master magnet comprises a conductor o^4 (Fig. 2) tapped from the conductor o leading from the conductor b referred to leading to the brake magnet, and said conductor o^4 is connected to the coil of the master magnet 303, said coil being connected by a conductor o^5 with the conductor o' leading to the

conductor b' leading in turn to the main negative line N.

When the car comes to a floor level, the brake magnet is deenergized to apply the brake and the master magnet 303 also is deenergized. This will permit its plunger to drop and close the switch 295, thereby completing the circuit to the pilot magnet 271 to energize the same. This will cause its armature to rock up and close the switch 267, thereby completing the circuit to the door opening solenoid 41. The energization of the latter causes its plunger 45 to be drawn upward, thereby rocking the bell crank 47 in a clockwise direction and opening the previously unlocked car and floor doors.

It requires greater power to pull the solenoid 45 up to open the doors than to hold said doors open. After the plunger has been pulled up by the solenoid a resistance 317 is introduced across the conductors x^2 and x^3 leading from the door opening solenoid 41, and the switch 258 referred to is mounted on a lever 319 having a spring 321 normally closing said switch. On the end of the plunger 45 is a lug 321 adapted to engage the lever 319 and open the switch 258 as the plunger 45 approaches its upward limit of movement. This will automatically introduce and render effective the resistance 317.

At the same time the door opening solenoid is energized to open the door, the timing solenoid 107 is energized. The circuit for this solenoid comprises a conductor e tapped from the positive line x referred to and connected to the coil of said timer, said coil being connected by a conductor e' with the conductor x^5 leading to the fixed contact 259. The rest of the circuit for the timer magnet solenoid is completed by the conductors and switches described for the circuit for the door opening solenoid including the switch 267 controlled by the pilot magnet. Therefore, when this switch is closed the circuit will be completed to the timer.

As stated the switch in the circuit to the pilot magnet is closed merely momentarily as the nub on the plunger of the master magnet 303 passes the switch 295. The energization of the pilot magnet is continued, however, after the opening of said switch and circuit. This is accomplished on the closing of the pilot magnet switch 267 through the conductor e (Fig. 2) leading from the positive line x , through the timer coil 107, conductor e' , switch 113, conductor x^4 , switch 267, conductor z leading to the car despatching push buttons, thence through conductor z^4 to the coil of the pilot magnet 271 and thence through the conductor z^5 to the negative line.

The timer solenoid being energized as described, its plunger 109 will be pulled gradually upward as checked by its dash pot until

the lug 111 on said plunger engages the switch 113 and opens the same. This will deenergize the door opening solenoid, thereby permitting its spring to become effective to thrust the plunger 45 downward and rock the bell crank 47 in a contra-clockwise direction and close the doors.

The opening of the switch 113 by the timer also breaks the circuit to the timer 10 solenoid, permitting its plunger to drop back to its position shown in Fig. 2 and breaks the circuit to the pilot solenoid 271, thereby permitting its switch 267 to open. The opening of the latter switch will interrupt the circuit to the door opening solenoid independently of the opening of said circuit by the switch 113 so that on the deenergization of the timer magnet 107 and the consequent closing of the switch 113 the circuit 20 to the door opening solenoid will not be again completed. The circuit to the door opening solenoid will only be completed on the reenergization of the pilot solenoid as described.

25 When the car door was opened, the cam finger 191 (Fig. 1) withdrew from the stem of the switch 183, thereby breaking the circuit to the magnet 143 for holding open the non-interference switch 223 and permitting said switch to close and connect with the contacts 221 and 225 in the circuit to the car despatching push buttons. On the closing of the car door, the cam finger 191 closes the switch 183 and thereby places 35 the circuit in readiness to be completed for starting the car on the pressing of a car despatching button.

Referring now to the car stop button 129, as stated this button is adapted to be pressed 40 when it is desired to arrest the car in the course of its travel from one floor to another. For example, the car may have been despatched to the fourth floor and the passenger may have changed his mind and decided to despatch the car to a different floor. He therefore presses the stop button and after he has brought the car to a stop presses the appropriate button to send the car to the floor desired.

50 The circuit controlled by the stop button comprises a conductor s (Fig. 2) tapped from the positive line α referred to and connected to a fixed contact 337 adapted to be connected by the switch 339 of the 55 stop button with a fixed contact 341. The latter is connected by a conductor s' with the coil of the stop magnet 291 referred to, said coil being connected by a conductor s^2 with the negative line. The armature 289 of the stop magnet carries the switch 220 referred to in the circuit for the magnets for shifting the levers for closing the circuits to the motor and for deenergizing the brake magnet. Therefore on the energization of 65 the stop button magnet 291, its armature

will be pulled up and open the switch 220^b, thereby deenergizing either the up or down magnet as the case may be for the levers for controlling the circuits to said motor and brake and thereby stopping the motor 70 and applying the brake.

It will be recalled the circuit for energizing the pilot magnet 271 for completing the circuit for energizing the door opening solenoid includes a switch 285 carried by the 75 stop button magnet armature 289. The pressing of the stop button, therefore, opens this switch and breaks the circuit to the pilot solenoid and prevents the car door from opening. This is important, since obviously 80 it would be undesirable to open the car door between floors.

The stop button is pressed merely momentarily to stop the car. It is, therefore, necessary to provide a circuit for continuing the 85 energization of the stop button magnet 291 after the momentary pressure on said stop button has been released. To accomplish this a conductor n (Fig. 2) is tapped from the conductor s leading from the positive line 90 α referred to and is connected to a fixed contact 349 adjacent the master magnet 303 (Fig. 2). This fixed contact is adapted to be connected by a switch 351 with a fixed contact 353. The switch is normally held 95 closed by a spring 355. The fixed contact 353 is connected by a conductor n' with a fixed contact 357 adjacent the stop button magnet 291. This fixed contact is adapted to be connected by a switch 359 with a fixed contact 361 connected by a conductor n^2 with the conductor s' referred to leading to the coil of the stop button magnet 291. The coil is connected by the conductor s^2 with the negative line as described. Therefore, 100 when the stop button magnet is energized, the switch 359 being then closed, the circuit will be completed to the coil and continue 105 the energization thereof.

The pressing of the stop-button not only 110 deenergized the brake magnet to apply the brake, but also deenergized the magnet 303 and permitted its plunger 305 to drop. The breaking of the circuit to the pilot solenoid 271 at the stop button magnet prevented the 115 opening of the car door by the dropping of the master magnet plunger 305, since it broke the circuit to the pilot magnet at the stop button magnet. After the nub 307 on the master magnet plunger has dropped 120 down past the arm 301 of the switch 295 there is no necessity for continuing the interruption of the circuit to the pilot solenoid at the stop button magnet. Therefore, the hold up circuit for the stop button magnet 125 should be broken. To accomplish this, the master magnet plunger is provided with a lug 363 (Fig. 2) adapted to engage and open the switch 357 and break the holding circuit to the stop button magnet. The 130

opening of this switch occurs after the nub 307 on the master magnet plunger has passed down out of range with the switch arm 301.

The dash pot for the timer 107 may be 5 adjusted to delay the closing of the doors until after a predetermined time interval has elapsed such as would be appropriate for average conditions. At times, however, the passengers may desire to start the car 10 without waiting for this time interval to completely elapse. This is accomplished automatically incidentally to the pressing of a push button in the car for starting the car. It will be recalled that this push button 15 controls two circuits, one passing through the pilot magnet 271, and one for completing the circuit for starting the car. The switch controlled by the push button is arranged between a set of contacts for one 20 circuit and a set of contacts for the other circuit. Consequently, on pressing the push button the initial movement of the switch will be away from one set and break the circuit to the pilot magnet, and its final 25 movement will bring it into engagement with the other set and complete the circuit for starting the car. The deenergization of the pilot magnet 271 permits its armature switch 267 to drop and break the circuit to 30 the timer solenoid 107 and the door opening solenoid 41. The deenergization of the latter will permit its spring to close the doors.

Thus two purposes are accomplished by 35 each of the car despatching push buttons in the car, thereby simplifying the construction and rendering the same easy to understand and operate.

Heretofore, so far as I am aware, when the car is at a floor level, it is necessary to 40 open both the floor level door and the car door manually against the strong resistance of a door check. This is an awkward and difficult operation requiring considerable strength. It is, therefore, desirable to be 45 able to open the doors merely by pressing the push button at the floor level.

To accomplish this a circuit is provided comprising a conductor h (Fig. 3) tapped from the conductor 2 referred to and leading 50 to a movable contact 364 adapted to be connected by the selector switch 239 referred to, with the fixed contact 364^a when said switch is in mid position on the arrival of a car at the floor level. The fixed contact 55 364^a is connected by a conductor h^3 with a fixed contact 364^b (Fig. 2) adjacent the master magnet 303 (Fig. 2). This contact is adapted to be connected to a fixed contact 364^c by a switch 364^d normally held open 60 by a spring 364^e. The switch has an arm 364^f projecting beneath the lower end of the master magnet plunger 305, the latter being adapted to engage and close said switch 364^d when said plunger is in its lowest position. 65 The fixed contact 364^c is connected by a

conductor h^4 with a coil for the pilot magnet 271, said coil being connected by a conductor h^5 with the negative line.

When the floor push button is pressed this will complete the circuit just described to 70 the pilot solenoid 271. The switch 364^a is opened by its spring 364^b when the car is running since then the master magnet 303 is energized and its plunger 305 is drawn up out of engagement with said switch, but 75 when the car is standing at a floor level the master magnet is deenergized and its plunger is down in a position to hold said switch closed. The energization of the pilot solenoid completes the circuit to the door opening solenoid 41, thereby opening the door. It also completes the circuit to the timer solenoid 107 which will serve to break the circuit to close the door after the predetermined time interval has elapsed as described. 80 85

The movable contact 364 referred to at the selector is engaged by the selector switch 239 whenever the car comes to a rest at a floor level and also momentarily closes said switch 90 in the transit of the car past the floor level, but while the car is traveling the hold up magnet 303 is energized and its plunger is drawn up away from the switch 364^a, thereby permitting the spring 364^b for the latter 95 to hold the switch open. This will interrupt the circuit and prevent the completion thereof by the pressing of a floor button at all times excepting when a car is at rest at a floor level. It therefore will be impossible 100 for a person at a floor level to press a button thereat and interfere with the passage of the car past such level.

It is possible that a passenger after entering the car may change his mind and decide 105 to leave the car after its door has automatically closed and before despatching the car to another level. Since the push buttons in the car are in the same circuit with the push buttons at the floor level, it will be possible 110 for him to press a push button in the car and thereby complete the circuit to the pilot solenoid through the selector switch 364 when the selector switch 239 is in mid position while the car is at a floor level. The 115 energization of the pilot magnet will complete the circuit to the door opening solenoid 41 and open the door in the manner described.

Next will be described the circuit for lighting the dome light 123 in the car. This circuit comprises a conductor w (Fig. 2) leading from a source of current to a long, fixed contact 365 adapted to be connected to a similar fixed contact 367 by a switch 369 mounted on a plunger 371 of a solenoid 373. The fixed contact 367 is connected by a conductor w' with the dome light 123 in the car. Said light is connected by a conductor w^2 with the negative line. 120 125 130

When the light controlling solenoid 373 is energized it will pull up its plunger and connect the switch 369 with the fixed contacts 365 and 367, thereby completing the circuit to the light.

- 5 The solenoid 373 is connected in the same circuit with the brake controlling magnet 19. To accomplish this a conductor *l* is tapped from the conductor *o* leading from the positive line *b* referred to for the brake magnet, said conductor *l* being connected to the coil of the light controlling magnet 373. This coil is connected by a conductor *l'* with the conductor *o'* leading to the conductor *b'* leading in turn from the brake magnet 19. Thus when the brake magnet is energized to release the brake on the starting of the car, the light controlling switch 373 will be energized and complete the circuit to and light the light in the car.

20 The brake magnet is deenergized on the stopping of the car and therefore the circuit described for the light controlling magnet also will be deenergized on the arrest of the car. This would cause the light to go out. It is desired, however, to maintain the light lighted while and for a time after the car is brought to rest. To accomplish this a circuit is provided comprising a conductor *w*⁴ (Fig. 2) tapped from the conductor *e* referred to leading to the door timer solenoid 107, said conductor *w*⁴ being connected to a coil for the light controlling magnet 373, said coil being connected by a conductor *w*⁵ with the conductor *w*³ referred to in the circuit for the door opening magnet. Thus when the circuits are completed for energizing the door opening solenoid 41 on the deenergizing of the master magnet 303, the circuit just described will be completed to the light controlling magnet 373 and continue to hold its switch 369 closed.

45 In order that the light may continue lighted during the interval between the opening of the brake circuit and the closing of the door opening circuit, the plunger 371 of the light controller magnet 373 may be connected to a piston 375 (Fig. 2) in a cylinder 377 having a controlling valve 399 permitting the gradual escape of air therefrom. Thus on the opening of the brake circuit and the consequent deenergization of the light controlling magnet 373, its plunger 371 will be retarded and permitted to move gradually 50 downward. The contacts 365 and 367 are made sufficiently long so that the switch 369 will not have an opportunity to leave the same before the door opening circuit is closed. On the occurrence of this event the light controlling magnet 373 will be again energized and pull its plunger upward, the light continuing lighted in the meantime.

60 The dash pot for the light controlling solenoid will also serve to delay the extinguishing of the light for a substantial length of

time after the timer magnet 107 has broken the circuit to the door opening solenoid 41 to initiate the closing of the door. This will prevent the light from going out until after the passenger of the car has had an opportunity to pass out of the car through the door and the door has had an opportunity to close.

65 To prevent a person from stumbling on entering or leaving the car a threshold light 75 381 may be provided in the car adjacent the door threshold thereof. The circuit for this light comprises a conductor *w*⁶ (Fig. 1) leading from the conductor *w*¹ referred to for the light 123 and connected to the light 80 381. This light is connected by a conductor *w*⁷ with the fixed contact 383 adapted to be connected to a fixed contact 385 by a switch 387 urged to engage said fixed contacts by a spring 389. To hold the switch 387 open 85 when the door is closed, the door is provided with a cam finger 391 adapted to engage a stem 393 on said switch. When the door is open this cam finger will move away from said stem and permit said switch to close. 90 The fixed contact 385 is connected by a conductor *w*⁸ with the conductor *w*² referred to leading from the dome light 123.

95 It will be apparent from the above that when the car door is opened the threshold light will be lighted and after the car door is closed the threshold light will be extinguished.

100 To automatically arrest the elevator car as it reaches its upper and lower limits of travel, it is provided with the usual cam 395 (Fig. 1) for automatically opening upper and lower switches 397 and 399 in a circuit comprising a conductor *v* (Fig. 3) tapped from the conductor *e* referred to leading 105 from the positive line, said conductor being connected to the usual slack cable switch 401, said switch being connected by a conductor *v'* with the lower switch 399 and the upper switch 397, the latter being connected by a conductor *v*² with a circuit breaker 403 (Fig. 3); the latter being connected by a conductor *v*³ with a blow-out magnet 405, the latter being connected by a conductor *v*⁴ with the main negative line N.

110 In electric elevators heretofore used it has been possible for a person to call the car to a floor level and then change his mind and not open the car door and use the car. This automatically rendered all of the car despatching buttons ineffective and prevented the call of the car to another floor level. The car could not be started until one had followed the stairs to the level where the car was stalled. Then on opening and closing the car door manually the non-interference switch was closed and the despatch buttons again became effective to operate the car.

115 120 125 130 By my invention the car if not in use will

always respond to the call thereof since every time it arrives at a floor level the car door will be automatically opened and closed and thereby render the car despatch buttons effective.

The automatic opening of the car and floor doors on the arrival of the car at a level and the provision for opening the doors merely by the pressing of a push button at a 10 floor level, serve as a great convenience to the users of the elevator, relieving them of the work and inconvenience of manually sliding the doors open, an operation frequently against the strong resistance of a 15 powerful door check which immediately tends to close the doors with consequent annoyance and likelihood of jamming or otherwise injuring the persons entering or leaving the car.

20 The timer serves automatically to hold the doors open a sufficient length of time to allow the passenger to enter the car, but does not delay the starting of the car if the time interval thereof is not required, since 25 the pressing of the push button in the car to despatch the same will automatically cut out the timer on the initial pressure thereon.

The automatic lighting of the dome light in the car for the required interval of time 30 furnishes the proper lighting of the car and with an economy of electricity while the car is not in use.

The threshold light is a feature which contributes to the safety of the passengers 35 with a slight expenditure of electricity since it is extinguished at all times excepting while the car door is open.

The above and other features described contribute to the production of an electric 40 elevator which can always be relied upon to operate with ease and satisfaction under all conditions and with complete safety to the passengers. After the car has been started by the pressing of a push button at 45 a floor it automatically comes to the floor level to which it is summoned and its door automatically opens to receive the passenger, and after he enters the car and pushes a button the door automatically closes and 50 the car travels to the floor desired and the door automatically opens to permit his exit from the car, all without further attention or operation by the passenger. As soon as the car has made a trip it can always be relied 55 upon to be in readiness to make the next trip.

It will be understood that while the invention has been described more particularly with reference to electric elevators, some features thereof are applicable to other 60 types of elevators.

Having described one illustrative embodiment of the invention without limiting the same thereto, what I claim as new and desire to secure by Letters Patent is:—

65 1. An elevator comprising, in combina-

tion, a car, means to despatch the same to any selected floor including a floor selector independent of the car; a door to control passage to and from the car, and means controlled by said selector for automatically 70 opening said door on arrival of the car at said floor.

2. An elevator comprising, in combination, a car, controlling elements corresponding to different floors, operating means for 75 automatically moving said car to and arresting the same at any selected floor on manual actuation of the element corresponding to such floor; a door, controlling means automatically to open said door on arrival of 80 the car at said floor, and means thereafter automatically to close said door without further manual operation.

3. An elevator comprising, in combination, a car, a motor therefor, a circuit for 85 said motor, a switch in said circuit, a magnet for operating said switch, a controlling circuit for said magnet including a floor selector switch device actuated with said motor and having provision for shifting said 90 switch and opening said motor circuit on arrival of the car at a selected floor; a door, and an electrical operating device therefor including a circuit controlled by said selector automatically to open the door on arrival of 95 the car at said selected floor.

4. An elevator comprising, in combination, a car, controlling elements corresponding to different floors, operating means for automatically moving said car to and arresting the same at any selected floor on actuation of the element corresponding to such floor; a door, means coöperating with said operating means automatically to open said door, means to hold said door open for a 100 predetermined time interval, and means automatically to close said door on the expiration of said interval.

5. An elevator comprising, in combination, a car, controlling elements corresponding to different floors, operating means for automatically moving said car to and arresting the same at any selected floor on actuation of the element corresponding to such floor, a door for the car, doors for the floors, 110 means to lock the car door, means to lock the floor doors, means coöperating with said operating means automatically to connect said car door with any of said floor doors, and means automatically to unlock said connected doors on the arrival of the car at a selected floor.

6. An elevator comprising, in combination, a car, controlling elements corresponding to different floors, operating means for 125 automatically moving said car to and arresting the same at any selected floor on actuation of the element corresponding to such floor, a door for the car, doors for the floors, means to lock the car door, means to lock 130

the floor doors, means automatically to unlock said doors on the arrival of the car at a floor, means coöperating with said operating means automatically to open said doors on the arrival of the cars at said floor, and means automatically to close and relock said doors.

7. An elevator comprising, in combination, a car, controlling elements corresponding to different floors, operating means for automatically moving said car to and arresting the same at any selected floor on actuation of the element corresponding to such floor, a door, and means coöperating with said operating means automatically to unlock, open, and close said door on the arrival of the car at said floor.

8. An elevator comprising, in combination, a car, controlling elements corresponding to different floors, operating means for automatically moving said car to and arresting the same at any selected floor on manual actuation of the element corresponding to such floor, a door, and controlling means for the latter coöperating with said operating means including an electric circuit, a switch in said circuit, a timer solenoid to operate said switch, and means to prevent said solenoid from actuating said switch until the expiration of a predetermined time interval following the opening of said door.

9. An elevator comprising, in combination, a car, switches corresponding to different floors, operating means for automatically moving said car to and arresting the same at a selected floor on actuation of the switch corresponding to such floor, a door, means coöperating with said operating means automatically to open said door on arrival of the car at said floor, and means controlled from the car for arresting the latter between floors without opening said door.

10. An elevator comprising, in combination, a car, controlling elements corresponding to different floors, operating means for automatically moving said car to and arresting the same at any selected floor on actuation of the element corresponding to such floor; a door on the car, and means controlled by the car operating means for automatically opening said door when the car has stopped at said floor.

11. An elevator comprising, in combination, a car, a door, controlling elements corresponding to different floors, operating means for automatically moving said car to and arresting the same at any selected floor on actuation of an element corresponding to such floor and including an electric circuit complete only when the door is closed, means controlled by the car operating means for automatically opening the door after the car has stopped at the selected floor and means for reclosing the door to render effective again said controlling elements.

12. An elevator comprising, in combination, a car, a door, controlling elements corresponding to different floors, operating means for automatically moving said car to and arresting the same at any selected floor on actuation of an element corresponding to such floor and including an electric circuit complete only when the door is closed, means controlled by the car operating means for automatically opening the door after the car has stopped at the selected floor and holding the same open and means including a push button to cut out said holding means and permit reclosing of the door to render effective again said controlling elements.

13. An elevator comprising, in combination, a car, electric operating means therefor including switches corresponding to different floors selectively operable to despatch the car to any floor, electric circuits for said switches; a door, means controlled by said operating means automatically to open the latter on the arrival of the car at a floor, and means to prevent control of the car from a floor while said car is in transit.

14. An elevator comprising, in combination, a car, controlling elements corresponding to different floors, operating means for automatically moving said car to and arresting the same at any selected floor on actuation of the element corresponding to such floor; a door, means coöperating with said operating means automatically to open and hold open said door for a predetermined time interval, and means for despatching the car without waiting for expiration of said interval.

15. An elevator comprising, in combination, a car, a door, operating means to despatch said car to any desired floor including a circuit and a switch in said circuit controlled by said door; means coöperating with said operating means automatically to open said door and break said circuit on arrival of the car at the selected floor, and means automatically to close said door and circuit without further manual operation.

16. An elevator comprising, in combination, a car, a door, operating means to despatch said car to different floors, electric controlling means for said operating means including a circuit having car despatching switches corresponding to said different floors and a door controlled switch, means coöperating with said operating means automatically to open said door and its switch on arrival of the car at a selected floor and prevent despatch of the car to another floor, and means automatically to close said door and its switch to allow despatch of the car to another floor without further manual operation.

17. An elevator comprising, in combination, a car, a door, electric controlling means, a set of car despatching switches on the car

corresponding to different floors, switches at said floors, operating means to transmit said car to and arrest the same at a selected floor on actuation of either a car or a floor switch corresponding to said floor, and means cooperating with said operating means automatically to open and close said door on arrival of the car at the selected floor.

18. An elevator comprising, in combination, a car, a door, electric controlling means, car despatching switches corresponding to different floors, operating means to transmit said car to a selected floor on actuation of the switch corresponding thereto, means automatically to open and close said door on arrival of the car at the selected floor.

15 19. An elevator comprising, in combination, a car, a door, controlling means including an electric circuit, car despatching switches on the car corresponding to different floors, operating means to transmit said car to a selected floor on actuation of the switch corresponding thereto, means automatically to open and close said door on arrival of the car at the selected floor, and means to open said door after the automatic opening and closing thereof while the car remains at said floor.

20 20. An elevator comprising, in combination, a car, a door, controlling means including an electric circuit, car despatching switches on the car corresponding to different floors, operating means to transmit said car to a selected floor on actuation of the switch corresponding thereto, means automatically to open and close said door on arrival of the car at the selected floor, and means to open said door operable from said car after the automatic opening and closing thereof while the car remains at said floor.

25 21. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from said car after the automatic opening and closing thereof while the car remains at said floor.

26 22. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

27 23. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

28 24. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

29 25. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

30 26. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

31 27. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

32 28. An elevator comprising, in combination, a car, a door, car despatching switches at different floors, operating means to transmit said car to a selected floor on actuation of the switch corresponding thereto, means automatically to open and close said door on arrival of the car at the selected floor, and means to open said door operable from the floor to open said door after the automatic opening and closing thereof while the car remains at said floor.

for automatically opening the door when the 65 car has completed a predetermined journey, holding the same open a predetermined time interval, and then automatically closing the same.

24. An elevator comprising, in combination, a car, means for causing the same to travel in its well, a door, and electrical operating means effective automatically to open the door when the car has arrived at a selected floor level and to hold the door open 75 a predetermined time interval, there being provision for varying the duration of said interval.

25. An elevator comprising in combination, a car having a door, a floor level door, 80 a latch on one of said doors, a channel on the other for receiving said latch and means for automatically moving said latch into said channel on the arrival of the car at a floor level.

26. An elevator comprising in combination, a car having a door, a floor level door, latch means, means for automatically unlocking said doors on the arrival of the car at a floor level and means for causing said 90 latch means automatically to connect said doors on the arrival of the car at said level.

27. An elevator comprising in combination, a car having a door, a floor level door, means for unlocking said doors on the arrival of the car at a floor level, and means controlled by said unlocking means for connecting said doors to permit one to be opened by the other.

28. An elevator comprising, in combination, a car having a door, a floor level door, a latch on one of said doors, a channel on the other for receiving said latch, means for automatically moving said latch into said channel on the arrival of the car at a floor 105 level, a controller for initiating movement of the car, and means to disengage said latch and channel on actuation of said controller.

29. An elevator comprising in combination, a car, a door, a brake for arresting the 110 car, electromagnetic means for releasing the brake including a circuit and electromagnetic means for automatically opening the car door on the breaking of the circuit for said electromagnetic brake releasing 115 means.

30. An elevator comprising in combination, a car, a door, and means for automatically opening said door including a circuit, a switch in said circuit, a pilot magnet for 120 controlling said switch, a circuit for said pilot magnet, a switch in the latter circuit and an electromagnetic means for controlling said switch.

31. An elevator comprising in combination, a car, a door and means for automatically opening said door including a circuit, a switch in said circuit, a pilot magnet for

controlling said switch, a circuit for said pilot magnet, a switch in the latter circuit and means susceptible of adjustment prior to movement of the car for automatically closing the latter switch on the arrival of the car at a selected floor level to energize said pilot magnet and complete the circuit for opening said door.

32. An elevator comprising in combination, a car, a door and means for automatically opening said door including a circuit, a pilot magnet for closing said circuit, a circuit for said pilot magnet and a magnet for closing said pilot magnet circuit automatically on the arrival of the car at a floor level.

33. An elevator comprising in combination, a car, a door, an electromagnetic brake for said car and means for automatically opening said door including a device connected to said door, a circuit for said device, a pilot magnet for closing said circuit, a circuit for said pilot magnet and means for automatically closing said pilot magnet circuit on deenergization of said electromagnetic brake to arrest the car.

34. An elevator comprising in combination, a car, a door and means for controlling said door including an operating device for opening and closing the same, an electric circuit for said device and means for automatically opening and closing said circuit to cause said device to open the door on the arrival of the car at a floor level and to cause said device to close the door on the expiration of a predetermined time interval.

35. An elevator comprising in combination, a car, a door and means for opening and closing said door including an electromagnetic device, a timing device, a circuit for said devices, and means governed by said timing device for opening and closing said circuit to cause said device to open the door on the arrival of the car at a floor level and to cause said device to close the door on the expiration of a predetermined time interval.

36. An elevator comprising in combination, a car, a door and means for controlling said door including a door opening magnet, a timing magnet, a circuit for said magnets, a switch in said circuit, means for automatically closing said switch to render said door opening magnet effective to open the door and a switch in said circuit controlled by said timing magnet for opening said circuit to permit the closing of the door.

37. An elevator comprising in combination, a car, a door and means for controlling said door including a door opening device, a timing device and electrical means for controlling said devices including a circuit therefor, a switch in said circuit, means for automatically closing said switch to render said door opening device effective to open the door on the arrival of the car at a floor

level and a switch in said circuit controlled by said timing device for governing the circuit to permit closing of said door.

38. An elevator comprising in combination, a car, a door and means for controlling said door including door opening means, door closing means energized by the opening of the door, timing means and electrical means for controlling said door opening means including a circuit, a switch in said circuit, means for automatically closing said switch on the arrival of the car at a floor level to render said door opening means effective to open the door and a switch in said circuit controlled by said timing means for rendering said door closing means effective to close the door.

39. An elevator comprising in combination, a car, a door and means for controlling said door including door opening means, electrical means for controlling said door opening means including a circuit, a switch in said circuit, a magnet for actuating said switch, a circuit for said magnet, means for automatically momentarily closing said magnet circuit on the arrival of the car at a floor level and means operable on the closing of said magnet switch for continuing the energization of said magnet.

40. An elevator comprising in combination, a car, a door, electrically controlled closing means therefor, a timing magnet, a circuit for controlling said door closing means, a switch in said circuit and means actuated by said timing magnet for moving said switch after a predetermined time interval to render said door closing means effective to close the door.

41. An elevator comprising in combination, a car, a door, and closing means for said door, an electric circuit controlling the same, a switch in said circuit and a timing device for automatically actuating said switch on the expiration of a predetermined time interval to render said door closing means effective to close the door.

42. An elevator comprising in combination, a car, a door, closing means for said door, a circuit electrically controlling said closing means and timing means for automatically controlling said circuit including a solenoid having a plunger and means for retarding the movement of said plunger on the energization of said solenoid to postpone the closing of the door until after the expiration of a predetermined time interval.

43. An elevator comprising in combination, a car, a door, and controlling means for said door including a solenoid having a plunger connected to said door, a timing solenoid having a plunger, a circuit for said solenoids, means to complete said circuit to open the door automatically on the arrival of the car at a floor level, door closing means energized on the opening of the door, a

- switch in said circuit actuated by said timing solenoid plunger and means for delaying the actuation of said switch by said plunger until after the expiration of a predetermined time interval.
44. An elevator comprising in combination, a car having a door, means including push-buttons for despatching the car to different floor levels, a circuit for said buttons, 10 means for automatically opening and closing said door each time the car arrives at a floor level, means for automatically interrupting said circuit on the pressing of any of said push-buttons to prevent interference by said buttons with the car when in use and means controlled by the opening and closing of said door for reestablishing the circuit to render said buttons again effective to again operate the car.
- 20 45. An elevator comprising in combination, a car having a door, means for causing the car to travel in its well, means for automatically opening said door on the arrival of the car at a floor level, means including 25 a push-button operable from within the car for arresting the latter between floors and means for preventing the operation of said door opening means between floors.
46. An elevator comprising in combination, a car having a door, means for opening said door including a circuit, a switch in said circuit, a magnet for actuating said switch, a circuit for said magnet, a switch in the latter circuit operable from the car 35 and adapted to be closed to energize said magnet and interrupt said first named circuit to prevent the operation of said door opening means between floor levels.
47. An elevator comprising in combination, a car having a door, means including 40 an electric circuit for causing the car to travel in its well, a switch in said circuit, means for automatically opening said door on the arrival of the car at a floor level including a circuit, a switch in the latter circuit, a magnet for controlling said switches, means including a circuit for energizing said magnet having a switch in the car adapted to be closed to energize said magnet 50 and operate said switches in the circuit for causing the car to travel in its well and the door opening circuit to arrest the car and prevent the automatic opening of said door.
48. An elevator comprising in combination, a car, a door, means for causing said car to travel in its well including motor means and an electric circuit therefor, a switch in said circuit, means for automatically opening said door on the arrival 55 of the car at a floor level including an electric circuit, a switch in said circuit, an electro-magnet for operating both switches, a circuit for energizing said magnet, a switch in said circuit operable from the car for closing the circuit to said magnet
- to open said first two mentioned switches and interrupt their circuits to arrest the car and prevent the automatic opening of said door.
49. An elevator comprising in combination, a car, a door, motor means for causing said car to travel in its well, a circuit for said motor means, a switch in said circuit, means for opening the car door including a circuit, a switch in said circuit, a stop magnet for controlling said switches 70 and a circuit for said magnet including a switch operable from the car to close said magnet circuit and open said switches.
50. An elevator comprising in combination, a car, a door, motor means for causing said car to travel in its well including a circuit, a switch in said circuit; means for automatically opening said door on the arrival of the car at the floor level including a circuit, a switch in said circuit, a magnet for opening said switches, a circuit for said magnet including a switch controlled by said magnet, a circuit for said magnet and a switch operable from the car for closing said last-named circuit to energize said magnet and thereby operate said switches to arrest the car and prevent the automatic opening of said door.
51. An elevator comprising in combination, a car having a door, means including 95 a circuit for causing the car to travel in its well, means including a circuit for opening the door when the car stops and means operable from the car to control said circuits and thereby arrest the car and prevent the 100 operation of said door opening means.
52. An elevator comprising in combination, a car having a door, means including 105 a circuit for causing the car to travel in its well, means including a circuit for automatically opening said door on the arrival of the car at a floor level, means including a circuit controlled from the car momentarily effective for interrupting said circuits and means for continuing the interruption of said circuits.
53. An elevator comprising in combination, a car having a door, means including 110 a circuit for causing the car to travel in its well, means including a circuit for automatically opening said door on the arrival of the car at a floor level, means including a circuit controlled from the car for interrupting said circuits to arrest the car and prevent the automatic opening of the door and 115 means for automatically opening said interrupting circuit on the starting of the car.
54. An elevator comprising in combination, a car, a light therefor, a circuit for said light, a brake for the car, a circuit for 125 said brake and means operable on the completion of said brake circuit for completing the circuit to said light.
55. An elevator comprising in combination, a car, a light therefor and means for 130

automatically lighting said light during and for a predetermined period after the time the car is in use.

56. An elevator comprising, in combination, a car, a light therefor, means for despatching said car on a journey of determined length, and means for thereby lighting the light for a limited period covering the time of said journey.

10 57. An elevator comprising, in combination, a car, a light therefor, means for despatching said car on a journey of determined length, and means for thereby lighting the light for a limited period ended at 15 a definite time after the completion of said journey.

58. An elevator comprising in combination, a car, a light therefor, a circuit for said light, a switch in said circuit, means for 20 controlling said switch including a circuit, means for completing said last-named circuit on the starting of the car, means for interrupting said last-named circuit on the arrest of the car and a circuit for continuing 25 the closing of said switch after the arrest of the car.

59. An elevator comprising in combination, a car having a threshold, a light adjacent to said threshold and means for automatically lighting said light for a predetermined time on the arrival of the car at a 30 floor level.

60. An elevator comprising in combination, a car, a door, means for causing said 35 car to travel in its well including a selector switch mechanism for automatically arresting the car at different floor levels and means for opening the door including a switch closed by the selector when the car is at a 40 floor level.

61. An elevator comprising in combination, a car, a door, means for causing the car to travel in its well and controlling means for the car including a floor selector switch 45 mechanism, a door opening circuit including a switch at a floor level and a switch controlled by said selector mechanism enabling the opening of the door on the closing of the switch at a floor level when the 50 car is at said level.

62. An elevator comprising, in combination, a car, means for despatching said car to a selected level, means for automatically opening and subsequently automatically closing 55 the door on arrival of the car at the level, and means including an operating device at the level for re-opening the door independently of movement of the car.

63. An elevator comprising in combination, a car, motor means for causing the car to travel in its well, a circuit for said motor means including a floor selector switch mechanism, a door, a door opening circuit, a switch in said circuit closed by said mechanism 60 when the car is at a floor level and

means operable from within the car for completing said door opening circuit to open the door when at said level.

64. An elevator comprising in combination, a car, a door, means for automatically 70 opening said door on the arrival of the car at a floor level, means for automatically closing said door and push-button controlled means for opening said door when the car is at said level. 75

65. An elevator comprising in combination, a car, a door, means for causing the car to travel in its well, controlling means for the car including a floor selector switch mechanism, a door opening circuit, a switch 80 in said circuit closed by said selector mechanism on the arrival of the car at a floor level and means operable from the car or from a floor level for completing said door opening circuit to open the door when the car is at 85 said level.

66. An elevator comprising in combination, a car, a door, motor means for causing said car to travel in its well, controlling means for said motor means including a floor 90 selector switch mechanism for arresting the motor means to stop the car at different floor levels, switches closed by said selector mechanism on the arrival of the car at different floor levels, circuits containing said 95 switches and controlling switches in said car and at said levels for completing said circuits when the car is at said levels and means controlled by said circuits for automatically opening the car door on the closing 100 of said circuits.

67. An elevator comprising in combination, a car, a door, means to cause said car to travel in its well, means automatically to open and close said door on arrival of the 105 car at a floor level and means including a switch in the car for opening said door after the automatic operation thereof.

68. An elevator comprising in combination, a car, a door, means to cause said car to travel in its well, means automatically to open and close said door on arrival of the car at a floor level and means including switches in the car and at the floor level alternatively operable for opening said door 110 after the automatic opening and closing thereof. 115

69. An elevator comprising in combination, a car, a door, means to cause the car to travel in its well, electrical means for 120 opening the car door when the car is at a floor level including a switch at said level and means to prevent said switch from being effective to open the door while the car is traveling. 125

70. An elevator comprising in combination, a car, a door, means to cause said car to travel in its well, electrical means for opening the door automatically on arrival of the car at a floor level, electrical means 130

for opening said door after the automatic operation thereof including a selector 27, a switch 364, closed by said selector when the car is at a floor level, a switch 364^a, means for opening the latter when the car is traveling and a circuit containing said switches for opening the door on the completion thereof.

71. An elevator comprising in combination, a car 1 having a door 33, means including a motor 17 for causing the car to travel in its well, means for automatically opening said door on arrival of the car at a

floor level, circuits for said motor and door opening means, switches 220^b and 285 in 15 said circuits and means 291 controlled from the car to shift said switches to stop the car and prevent automatic opening of the door.

In testimony whereof, I have signed my name to this specification, in the presence of 20 two subscribing witnesses.

JOSEPH R. JACKSON, Jr.
